CLAIM

The ornamental design for a drinking mug, as shown and described.

DESCRIPTION

FIG. 1 is a perspective view of a drinking mug of the present invention;

FIG. 2 is a right side view thereof;

FIG. 3 is a left side view thereof;

FIG. 4 is a top view thereof;

FIG. 5 is a bottom view thereof showing the location of the unclaimed structure in broken lines;

FIG. 6 is a bottom view like FIG. 5 in which the broken lines have been removed; and,

FIG. 7 is a perspective view thereof in use condition.

The broken lines shown in the figures are for the purpose of illustrating environment only and form no part of the claimed design.
